EGG INSPECTION DEVICE

Adolf Schwarzkopf, Miami Beach, Fla.

Application April 29, 1933, Serial No. 668,639

5 Claims. (Cl. 88—14.5)

My invention relates to egg inspection devices, and particularly to a device of this character intended and adapted for use in testing or inspecting a plurality of eggs simultaneously to ascertain

5 their freshness, purity and character.

An object of this invention is to provide a device of this character which can be placed in grocery stores, markets and other places where eggs are sold or handled, and which functions 10 automatically to project a strong light through the eggs to thus enable the consumer to determine exactly the quality of the eggs at the time of purchase or use.

Another object is to so construct the device that 15 as the eggs are fitted in an appropriate receptacle and are moved into the device the light is automatically projected through the eggs, and as the eggs are removed following the test the light will be automatically extinguished.

20 A further object is to provide a testing device which will take a dozen eggs more or less and, disposing these to all be readily and clearly within the sight and view of the user, will project light strongly and substantially evenly 25 through all of the eggs at one time, to thus allow a determination of the character of all of the eggs and a comparison as to the color, quality and contents.

Yet another object is to provide a device of 30 this character which is of simple and inexpensive construction, and which can be readily and efficiently operated by individual customers or others not especially skilled or instructed, and which at the same time economizes on the electric current used for illumination, as the current is consumed only during the interval when a test is being made.

With the above and other objects in view, which will be apparent to those skilled in the art, 40 my invention includes certain novel features of construction and combinations of parts which will be hereinafter set forth in connection with the drawings and then pointed out in the claims.

In the drawings:

45 Figure 1 is a view in front elevation of a device constructed in accordance with my invention.

Fig. 2 is a view in end elevation, with some parts broken away to more clearly illustrate the 50 operating mechanism.

Fig. 3 is a fragmentary perspective view of the light control switch.

Fig. 4 is a fragmentary view in elevation of the structure shown in Fig. 3.

55 The case 1, which can be constructed of sheet

metal or any other suitable material, is preferably made to be of substantially rectangular form in plan and has an opening 2 through one side thereof closed by a door 3 hinged or swingably mounted at its lower side to open outwardly and 5 downwardly.

The top 4 of the case, which is preferably of pyramidal form, has an opening through the middle portion thereof and a viewing tube 5 extends upwardly around this opening. The tube 10 5 is shaped at its upper end 6 to substantially conform to the frontal portion of the head around the eyes so that as the head is lowered and the eyes are located to look downwardly through the tube 5 this edge 6 will substantially conform to 15 the face to preclude the penetration of light from the outside through the tube 5 into the upper portion of the case. This edge 6 is preferably rolled over and beaded, as at 7, to ease contact with the face and prevent injury, and if desired 20 this rolled portion might be covered with suitable padding, or otherwise suitably treated to present an easy and pleasant contacting surface or edge.

The opening 2 through the front side of the 25 case is formed at an elevation above the bottom member 8, and a partition or shield rest 9 is mounted transversely within the case adjacent to the lower side of opening 2 and at an elevation spaced above the bottom member 8. This 30 shelf or partition portion 9 has an opening 10 formed through the middle portion thereof, and a reflector 11 is mounted beneath this opening 10.

A support 12 is slidably mounted on the upper side of the opening 10, and this support has an 35 egg tray 13 carried therewith, the egg tray being provided with a plurality of egg receiving cups or rests 14 and being made substantially continuous and opaque in all portions outside of these cups or rests 14. In the present instance I have 40 illustrated a tray 13 having twelve cups or rests 14 grouped in two parallel lines, to thus take a dozen eggs, but it is to be understood that a greater or lesser number of cups or rests can be used.

45 A glass or other transparent covering 15 is preferably provided for the opening 10, and electric lamp sockets 16 are provided at one side within the case to receive and hold electric lamp bulbs 17 to be preferably substantially centered between 50 the two rows of egg cups within the tray 13. As illustrated in Figure 1, it is preferable that the electric lamp bulbs be so centered and spaced that each bulb will substantially directly cast its rays of light upon the lower ends of two adj- 55

cent transverse rows of eggs, and thus when the several egg cups or rests 14 of the tray 13 have eggs therein and the tray is moved to the position shown in full lines in Fig. 2, where it is centered to cover the opening 10, the light rays will be projected substantially directly through each and every one of the eggs, so that as a party desiring to view the eggs looks through the tube 5 each egg will be illuminated by light rays projected from the lower side, while all light, both artificial and natural, is excluded from the upper part of the case, thus insuring maximum and substantially uniform illumination of each of the eggs so that the observer can not only judge as to the contents and interior character of each individual egg, but comparison of the eggs can be readily made for uniformity of color, quality, and other characteristics.

As stated, the slide member 12 carries the tray 13 and this slide member and the tray can be withdrawn through the opening 2 for ready access to the eggs for placement, removal and the like. It is essential that provision be made to insure proper centering of the tray structure 13 over the opening 10, and desirable that provision be made for uniform withdrawal so that the egg tray is always presented in substantially the same position when outside of the case. With this in mind, I provide operating links 18 pivoted at their upper ends adjacent the sides of the case 1 with their lower ends free to swing forward and back adjacent to the ends of the opening 10. These swinging ends of the links 18 are provided with slotted openings 19 receiving pins 20 associated with the sliding member 12, and thus as the links 18 are swung in one direction, as for instance to the right to the full line position illustrated in Fig. 2, the slide member 12 will be moved into the case 1 centering the egg tray 13 thereof over the opening 10; whereas, when the links 18 are swung to the opposite position, as indicated by the dotted lines in Fig. 2, the slide member will be moved to extend the egg tray 13 through the opening 2, to thus be completely and freely accessible from the outside of the case. To accomplish this swinging movement of the links 18 automatically, when door 13 is opened and closed, I provide suitable bearing ears 21 on the door at points spaced from the hinge mounting thereof, 50 and then pivotally connect operating links 22 with these bearing ears and with the swinging links 18 adjacent to their lower slotted ends. With this construction and interconnection, the links 18 are swung to the full line position, referring to Fig. 2, when the door is closed and to the dotted line position when the door 3 is opened, the sliding member 12 and the egg tray being consequently and accordingly moved. A slide rest 23 is preferably provided on the inner side of the door 3 to engage beneath the outer end of the slide member 12 and thus support the egg tray 13 in proper elevation when moved to the extended position.

The lamp bulbs 17 will be supplied with electric current from any suitable source, and through any circuit connection, some of the wires of which are indicated at 24. It is desirable that the lamp bulbs 17 and the circuit connections thereto be cut out or deenergized, except during such intervals as the egg tray is completely within the case in the full line position shown in Fig. 2, which is the egg testing position, and with this in mind I provide a switch structure 25 in suitable connection in circuit wiring 24 to normally have its parts in the circuit opening position, as best illustrated in Fig. 4. A switch closing handle or

plate 26 is associated with a movable part of the switch 25 and is located within the case to be engaged by a portion of the sliding member 12, or other movable part of the mechanism, so that when the egg tray is in the egg testing position this switch handle or plate 26 is engaged to close the switch and thus energize the lamp bulbs. 5

With this arrangement, the door 3 serves, when moved to the closed position, to properly center the egg tray and to automatically close the switch 10 to energize the lamp bulbs; and due to the location of the lamp bulbs and the provision of the reflectors, each and every one of the eggs is substantially equally and directly illuminated with light rays cast upon its lower side to penetrate 15 through the egg. When the door 3 is opened the switch again opens and as the egg tray is slid out through the opening 2, to give access to the eggs, the supporting rest 23 of the door holds the egg tray in properly supported position. A handle 27 is preferably provided for easy manipulation and operation of the door.

If desired, shield plates 28 can be provided within the case 1 over the swinging links 18 and the operating links 22, to thus avoid attracting the eye from a concentrated view upon the eggs and the walls of the upper portion of the case might be blackened or otherwise treated to avoid reflections and otherwise aid in the visibility or avoid attracting the eye from the eggs. In any 30 event, all of the eggs are presented conveniently within a single field of vision for the eyes when looking down through the open end of tube 5, and all of the eggs are substantially equally illuminated for ready and efficient comparison of 35 the color and other characteristics of the eggs individually and collectively.

While I have herein shown and described only certain specific embodiments of my invention and have suggested only certain possible modifications, it will be appreciated that changes and variations can be made in the form, construction, arrangement and mounting of the parts, in the materials used, and in many other respects, without departing from the spirit and scope of my invention. 40

I claim:

1. An egg inspection device comprising, with a case having illuminating means at one end and an inspection opening at the other end provided with a lateral opening intermediate, an egg tray slidable through said opening to a position within the case intermediate said source of light and said opening and to a position outside the case to be entirely accessible, a closure for said opening to exclude outside light when eggs in the tray are being viewed, and a connection between said closure and the egg tray to move said egg tray to the viewing position when the closure is closed and to the extended position when the closure is opened. 50

2. An egg inspection device comprising, with a case having illuminating means at one end and an inspection opening at the other end provided with a lateral opening intermediate, an egg tray slidable through said opening to a position within the case intermediate said source of light and said opening and to a position outside the case to be entirely accessible, a closure for said opening to exclude outside light when eggs in the tray are being viewed, a connection between said closure and the egg tray to move said egg tray to the viewing position when the closure is closed and to the extended position when the closure is opened, and means actuated by said tray to 65

render the illuminating means operative only when the egg tray is in a position to be viewed.

3. An egg inspection device comprising, a case having an opening through the upper part thereof, a viewing tube associated with the opening, a lamp bulb within the case at a point opposite said opening, said case having an opening through the side wall thereof intermediate the viewing opening and the location of the lamp bulb, an egg tray slidable into and from said case through said lateral opening, a door swingably mounted to close said opening, and a link connection from said door to the egg tray to move said egg tray into the case into viewing position when the door is closed and to withdraw the tray to be completely accessible when the door is opened.

4. An egg inspection device comprising, an upright case having an opening through its upper portion provided with a viewing tube, a supporting partition carried transversely within said case spaced from the bottom thereof and provided with an opening in its middle portion, said case having a door opening through one side thereof above said partition, a lamp bulb carried in the lower part of the case beneath the opening of said partition, an egg tray slidably mounted on said supporting partition movable to one position to be substantially centered over the opening thereof and to another position through the door opening to be entirely accessible outside the case,

a door to close said door opening, and link connections from said door to the egg tray to move said tray into the case over the opening of the partition thereof and to withdraw the egg tray to be entirely accessible when the door member is opened.

5. An egg inspection device comprising, an upright case having an opening through its upper portion provided with a viewing tube, a supporting partition carried transversely within said case spaced from the bottom thereof and provided with an opening in its middle portion, said case having a door opening through one side thereof above said partition, a lamp bulb carried in the lower part of the case beneath the opening of said partition, an egg tray slidably mounted on said supporting partition movable to one position to be substantially centered over the opening thereof and to another position through the door opening to be entirely accessible outside the case, 20 a door to close said door opening, link connections from said door to the egg tray to move said tray into the case over the opening of the partition thereof and to withdraw the egg tray to be entirely accessible when the door member is opened, 25 and circuit connections to said lamp bulbs and a switch in said circuit closed by movement of the egg tray into a position for viewing and open otherwise.
